United States Patent Office

Des. 204,829
Patented May 17, 1966

204,829

TOTE BOX

Richard G. Angell, Jr., 119 S. 5th Ave., Highland Park,
N.J., and John J. Marshall, 592 Locust St., Somerville,
N.J.

Filed May 25, 1965, Ser. No. 85,448

Term of patent 14 years

(Cl. D58—12.6)

FIG. 3.

FIG. 4.

FIG. 5.

FIGURE 4 is a partial sectional view on an enlarged scale taken along the line 4-4 of FIGURE 2; and

We claim:

The ornamental design for a tote box, substantially as shown.
